(57) **CLAIM**

The ornamental design for a fish pond ice melting device as shown and described.

DESCRIPTION

FIG. 1 is a perspective view of a fish pond ice melting device showing my new design;

FIG. 2 is another perspective view thereof;

FIG. 3 is a front view thereof;

FIG. 4 is a back view thereof;

FIG. 5 is a left view thereof;

FIG. 6 is a right view thereof;

FIG. 7 is a top plan view thereof; and,

FIG. 8 is bottom plan view thereof.

The broken lines in the drawings are for the purpose of illustrating portions of the fish pond ice melting device and form no part of the claimed design.
